Primary Examiner — Cynthia R Underwood(74) *Attorney, Agent, or Firm* — Soquel Group LLC(57) **CLAIM**

The ornamental design for serving platter, substantially as shown and described.

DESCRIPTION

FIG. 1 is a front elevation view of a serving platter showing our new design;

FIG. 2 is a top view thereof;

FIG. 3 is a side elevation view thereof;

FIG. 4 is a front perspective view thereof;

FIG. 5 is a back perspective view thereof;

FIG. 6 is a front elevation view of another embodiment of a serving platter showing our new design;

FIG. 7 is a top view of the serving platter of FIG. 6;

FIG. 8 is a side elevation view thereof;

FIG. 9 is a front perspective view thereof; and,

FIG. 10 is a back perspective view thereof.

The broken lines represent portions of the structure that form no part of the claim.
